UNITED STATES PATENT OFFICE.

FREDERICK K. VIAL, OF LA GRANGE, ILLINOIS, AND THOMAS FITZSIMMONS, OF DENVER, COLORADO, ASSIGNORS TO GRIFFEN WHEEL COMPANY, OF CHICAGO, ILLINOIS, A CORPORATION OF ILLINOIS.

COPE RAMMERS.

Application filed May 14, 1923. Serial No. 638,718.

This invention relates in general to foundry practice, and has more particular reference to the provision of rammers for use in connection with jolt machines for compacting the sand. While the invention will hereinafter be described in connection with the forming of car wheel molds, it will be understood that from many aspects it has other and more general application.

10 A principal object of the invention is the provision of co-operating rammers which will give desired compactness to the sand in the flask and particularly to certain parts thereof. In the ramming of car wheel molds 15 it is of great importance that the sand about the rim and flange of the wheel and adjacent the chill be properly rammed and compacted and our invention has particular benefits when used in this connection.

20 Another important object of the invention is the provision of rammers which can be employed with jolt machines with such certainty and efficiency of action that the ramming of the sand may be uniformly timed 25 into a close cycle of foundry operation with resultant uniform high output per equipment and labor involved.

Numerous other objects and advantages of the invention will be apparent as it is better understood from the following description, which, taken in connection with the accompanying drawings, discloses a preferred embodiment thereof.

30 On the drawings,
35 Figure 1 is a section taken through a car wheel mold and showing my cope rammer in position. It will, however, be understood that this is purely illustrative and not a condition arising in actual service;

40 Fig. 2 is a partial top plan view of cope rammer and

Fig. 3 is a side elevation thereof;

Fig. 4 is a bottom plan view of the same;

Fig. 5 is a section on the line 7—7 of Fig. 45 and

Fig. 6 is a section taken substantially on the line 8—8 of Fig. 4.

Referring to Fig. 1, reference character 11 indicates the drag and reference character 50 12 the cope. The drag in the present instance is merely an outer shell, the chill 14 being arranged between said cope and drag. The cope comprises outer bounding walls and an inner hub receiving portion or dish

15 connected at intervals about the cope with the outer wall by braces or ribs 16. The cope has an outer flange 17 adapted to rest upon the chill when the flask is assembled. In Fig. 1 reference character 18 indicates the cast wheel, reference character 19 its rim and reference character 21 its hub.

The cope rammer is shown in detail in Figs. 2 to 6. This consists of two parts, namely, an outer part 31 for ramming the rim and web of the wheel and a second part 32 for ramming within the central member or dish 15 of the flask part. These parts are mounted for conjoint movement in lifting them into and out of position and for independent ramming action. To this end brackets 33 are 65 mounted upon the top or back of the rammer part 31 and this provides bearings 34 through which slidably pass bolts 35 taking at their lower ends into the rammer part 32 and engaged at their upper ends in a cross-member 36 carrying a U-bolt 37 to permit power handling of the rammer. Handles 38 are provided so that the rammer may be lifted or guided into and out of action by hand. By means of this construction the 70 rammer 32 will be able to give relatively to the rammer 31 whenever a variation of sand is present within the dish or in a hub receiving portion. In other words, the sliding mounting of the rammer 32 on the brackets 75 33 permits this rammer 32 to adjust itself to the quantities of sand within the dish 15, while at the same time permitting the simultaneous ramming by means of the two rammers 31 and 32.

80 The rammer part 31 is provided with a plurality of downwardly extending projections 41 adapted to enter between the braces or ribs 16 of the cope. These projections have downwardly extending lips 42 at their ends and centrally disposed extensions 43 adapted to ram the sand in the dished part of the wheel rim. The rammer part 32 is hollow at its center at 44 to receive the sectional dish 45 and this rammer part is faced off at 46 on the curve shown to round off the sand about the dish opening.

90 In the making of a mould, the drag 11 is first placed over a suitable pattern, which is positioned on a jolt machine and filled with moulding sand or the like in the usual manner. The drag rammer is then brought over the drag and lowered into the sand, prefer-

ably by means of a crane and controlled by hand. The jolt machine is then operated and due to the weight of the drag rammer, the sand is compressed in accordance with 5 the lower surface of the drag rammer. The cope 12 is then similarly treated and the mould is then assembled as shown in Figure 1, with the chill ring 14 between the cope and drag and the several cores set in position, 10 after which the metal may be poured.

It is thought that the invention and many of its attendant advantages will be understood from the foregoing description, and it will be apparent that various changes may 15 be made in the form, construction and arrangement of the parts without departing from the spirit and scope of the invention or sacrificing all of its material advantages, the form hereinbefore described being merely a 20 preferred embodiment thereof.

We claim:

1. In combination with a cope for moulding car wheels, said cope including an outer cylindrical member and an inner dish joined 25 to said outer member by spaced ribs to receive the sand to be rammed, a cope rammer therefor, comprising a main ramming weight having a central aperture and provided on its under side with a plurality of spaced 30 apart depending projections adapted to enter between the spaced apart braces or ribs of the cope, and a second weight mounted within the framework of said first member and relatively movable with respect thereto, said 35 second weight having a central aperture to receive a sectional head and provided with a curved under surface to round off the sand about the dish opening.

2. A flask rammer for car wheel molds, 40 comprising a plate-like member apertured in the center and provided with substantially radially disposed depending projections, said plate having movably mounted thereon and disposed substantially above the open portion 45 of said plate, another weight in the form of an annulus, the said central perforation of which is large enough to receive a sectional head, the bottom wall of said second weight being curved in cross-section.

50 3. A flask rammer for car wheel molds, comprising a weight consisting of a plate formed with a central perforation, said plate having on its under side a series of substantially radially downwardly projecting fingers 55 spaced apart, said plate having an upstanding bracket adjacent its central opening and a second weight in the form of a centrally apertured member mounted on said bracket for vertically shifting movement.

60 4. A flask rammer for car wheel molds, comprising a plate-like weight having a central aperture so that the said weight can ram the sand in the flask part between the outer member of the flask part and the central dish and having depending fingers pass-

ing through the ribs joining the outer members in the dish, supports on said weight and a second weight carried by said supports adapted to lie in the central aperture of said first weight, the said second weight likewise having a central aperture to receive the sectional head. 70

5. A flask rammer for car wheel molds, comprising a first weight having a central aperture provided with depending spaced apart fingers and a second weight separated from said first weight and adapted to overlie the aperture of said first weight, said second weight having a central aperture. 75

6. A flask rammer for car wheel molds, comprising a weight having a central aperture provided with depending spaced apart fingers, a second weight mounted on said first weight so as to overlie the central aperture thereof, said second weight having a central aperture adapted to receive a sectional head, the bottom wall of said second weight being curved from its outer periphery downwardly toward the inner edge of the inner wall of 85 its aperture. 90

7. A flask rammer for car wheel molds, comprising a weight in the form of a circular plate provided with depending spaced apart fingers and provided with a relatively large central opening, a pair of upstanding brackets adjacent said opening, said brackets being provided with inwardly projecting bearings, bolts slideable through said bearings, a second substantially cylindrical weight provided with a central aperture having threaded openings to threadedly receive said bolts, the bottom portion of said second weight being curved downwardly and inwardly from its outer wall to said opening, and a cross yoke carried by the upper end of said bolts and being constructed and arranged to permit said weights to be lifted. 100 105

8. A flask rammer for car wheel molds, comprising a weight in the form of a substantially circular plate having a relatively 110 large central opening and provided on its under surface with substantially radially spaced apart depending fingers of tapering cross-section, said fingers being deeper at their outer ends and inclined toward their inner ends, the inner ends of said fingers having downwardly extending lips. 115

9. In combination with a flask part having inner and outer cylindrical parts united by spaced ribs for receiving sand to be rammed, a rammer comprising interconnected inner and outer weights, each formed with a central perforation, one of said weights registering with the aperture in the other weight. 120 125

10. In combination with a flask part having inner and outer cylindrical parts joined by spaced apart ribs, a rammer comprising inner and outer weights, adjustably interconnected, each of said weights having under- 130

neath ramming surfaces suitably shaped and each of said weights having hollow central apertures, one of said weights being adapted to register with the central aperture of the 5 other weight.

11. In an apparatus for moulding car wheels, in combination with a flask part including inner and outer cylindrical members spaced apart and joined by spaced apart 10 ribs, a rammer comprising inner and outer weights, each having central openings, one of said weights lying between the inner and outer members of the flask part and the other of said weights being arranged to lie within 15 the inner member of the flask part, said weights being wholly loose and being capable of being jolted so as to ram the sand between the inner and outer members of the flask part and between the central opening of the inner 20 member of the flask part.

12. An apparatus for moulding car wheels comprising, in combination with a flask part

having inner and outer spaced apart cylindrical members adapted to receive sand, inner and outer weights interconnected and 25 adapted loosely to lie on the sand between said inner and outer members and within the inner member, said weights having bottom surfaces suitably formed to ram the sand as desired. 30

13. The combination of a mold part for use in the casting of car wheels and having internal sand supporting members or braces, with a ramming weight comprising a body arrangeable above the sand deposited in the 35 said mold part and having projections arranged to pass between said sand supporting braces and shaped to correspond with the face of the pattern beneath the sand, whereby to give desired compactness in the ramming to each portion of the surface of the 40 pattern.
